ice cracking machine, which is particularly adapted to convert ice cubes into cracked ice in any degree of fineness desired, and to convert large solid cakes of ice into cracked ice, and to do this in a small unit which is inexpensive to manufacture, reliable in operation, and which is particularly adapted to convert cubes of ice into cracked ice in a fine degree of fineness.

UNITED STATES PATENT OFFICE

2,610,803

ICE CRACKER

John R. Bayston, Los Angeles, Calif.

Application July 16, 1949, Serial No. 105,100

3 Claims. (Cl. 241—255)

1

The present invention relates to ice cracking machines and has particular reference to a small motor driven machine adapted to convert ice cubes into cracked ice in any degree of fineness desired.

Numerous ice cracking machines have been devised and used in the past, but so far as known, the small units heretofore designed to produce cracked ice from a supply of cubes have been subject to clogging and jamming to an extent that has prevented their successful operation, while devices designed to shave ice from large, solid cakes have been objectionable due to their size and inherently expensive construction.

It is, therefore, the primary aim of the present invention to provide an ice cracking machine that is dependable and efficient in use, yet is of extremely simple mechanical construction and adapted to mass production methods of manufacture so that it may be produced at a cost low enough to find a ready acceptance in any establishment that uses cracked ice, even the smaller restaurants, bars and soda fountains which do not use enough of the product to justify an expensive machine.

The manner in which the objects of the present invention are accomplished is best illustrated in the drawings of the present specification, wherein:

Figure 1 is a vertical sectional view of an ice cracking machine according to these teachings, the view being taken substantially on the plane of the line 1—1 of Figure 2;

Figure 2 is a plan sectional view taken substantially on the plane of the line 2—2 of Figure 1;

Figure 3 is a detail sectional view taken substantially on the plane of the lines 3—3 of Figures 1 and 2; and

Figure 4 is a front elevational view of the adjustable breaker plate employed in the machine.

The machine comprises a frame generally indicated at 10 having a mounting bracket 11 by which it may be secured to any convenient support. The frame is an integral casting including a vertical plate 12 which forms one wall of the housing for the operating parts of the device, and a horizontal plate 13 on which a driving motor 14 is carried. The driving motor serves to rotate a disc-shaped rotor 15, the hub 16 of which is secured to the motor shaft 17 by set screws 18. The plate 12 of the frame is apertured at 19 to provide a clearance around the hub 16, so that the rotor turns free of the plate and is held in spaced relationship therefrom,

so that the disc 15 can rotate in the housing. The plate 12 is secured to the frame 10 by machine screws 20, and the plate 13 is secured to the frame 10 by machine screws 21. The plate 13 is secured to the frame 10 by machine screws 22. The plate 13 is secured to the frame 10 by machine screws 23. The plate 13 is secured to the frame 10 by machine screws 24. The plate 13 is secured to the frame 10 by machine screws 25. The plate 13 is secured to the frame 10 by machine screws 26. The plate 13 is secured to the frame 10 by machine screws 27. The plate 13 is secured to the frame 10 by machine screws 28. The plate 13 is secured to the frame 10 by machine screws 29. The plate 13 is secured to the frame 10 by machine screws 30. The plate 13 is secured to the frame 10 by machine screws 31. The plate 13 is secured to the frame 10 by machine screws 32. The plate 13 is secured to the frame 10 by machine screws 33. The plate 13 is secured to the frame 10 by machine screws 34. The plate 13 is secured to the frame 10 by machine screws 35. The plate 13 is secured to the frame 10 by machine screws 36. The plate 13 is secured to the frame 10 by machine screws 37. The plate 13 is secured to the frame 10 by machine screws 38. The plate 13 is secured to the frame 10 by machine screws 39. The plate 13 is secured to the frame 10 by machine screws 40. The plate 13 is secured to the frame 10 by machine screws 41. The plate 13 is secured to the frame 10 by machine screws 42. The plate 13 is secured to the frame 10 by machine screws 43. The plate 13 is secured to the frame 10 by machine screws 44. The plate 13 is secured to the frame 10 by machine screws 45. The plate 13 is secured to the frame 10 by machine screws 46. The plate 13 is secured to the frame 10 by machine screws 47. The plate 13 is secured to the frame 10 by machine screws 48. The plate 13 is secured to the frame 10 by machine screws 49. The plate 13 is secured to the frame 10 by machine screws 50. The plate 13 is secured to the frame 10 by machine screws 51. The plate 13 is secured to the frame 10 by machine screws 52. The plate 13 is secured to the frame 10 by machine screws 53. The plate 13 is secured to the frame 10 by machine screws 54. The plate 13 is secured to the frame 10 by machine screws 55.

2

in order that it is supported only by the bearings on which the motor shaft is carried. An adjusting screw 20 is provided to hold the disc in proper longitudinal relationship with the motor shaft. The rotor 15 is provided with a plurality of tapered conical teeth 21 arranged in radial rows extending outwardly from the center of the disc to its outer edges, as shown in Figure 3. The rotor 15 is enclosed within a cast metal housing 25 secured to the plate 11 by machine screws 25, and provided with an upwardly extending, flared ice chute 26. The opposite side of the housing includes a wall portion 27 lying closely adjacent the teeth of the rotor on one side of the disc, but on the other side of the center line of the disc the wall is offset outwardly as shown at 28 (Fig. 2), so as to provide a generally rectangular ice chamber defined by the walls 28, 29 and 31. An ice breaker plate 32 is mounted in this chamber on a pair of pivot studs 33 which extend through the walls 28 and 31, respectively. The breaker plate 32 extends inwardly and downwardly toward the rotor 15 and is provided on its inner face with a series of tapered conical teeth 34 disposed in a curved line starting from a point adjacent the center of the disc 15 and extending outwardly and upwardly, as shown in Figure 3. In this figure, it will be seen that when the disc 15 is revolving in counter-clockwise direction, the teeth 21 enter the ice chamber from one side and swing in an arcuate movement inwardly and downwardly. As the disc revolves, the teeth 21 mesh between the teeth 34 of the breaker plate, so that ice within the chute is crushed by the combined action of both sets of teeth.

It is to be particularly noted, however, that the teeth of the breaker plate are so disposed that the outermost teeth are the first to mesh, followed in rapid succession by each succeeding pair of teeth extending inwardly toward the center of the rotor. This performs an important function, in that it tends to move the ice inwardly toward the center of the rotor and effect what we may term a "combing" action on the ice, so that the cubes are fed toward the center of the disc where the breaking force of the teeth is greatest.

The degree of fineness of the ice produced by the machine can be regulated as desired by the thumb screw 35 threaded through a side wall 36 of the ice chamber at a point below the inwardly tapered neck 37 and bearing against the lower end 38 of the breaker plate 32. Thus by loosening the screw 35, the teeth 21 and 34 move into

widely spaced relationship and produce coarsely cracked ice, while if the screw 35 is threaded in fully the teeth 34 are held in close mesh with the teeth 21, and a finely pulverized product is produced.

Having thus described my invention, what I claim as new and desire to secure by United States Letters Patent is:

1. In an ice cracking machine, in combination, a rotor comprising a flat disc rotatable on a horizontal axis, with a plurality of teeth on one surface thereof and disposed in radial lines extending outwardly from the center toward the edges of the disc, a breaker plate overlying an upper quadrant of the rotor disc and adjacent the teeth thereon, said breaker plate having a curved marginal edge lying in a plane spaced from but generally parallel with the plane of rotation of the disc and carrying a series of teeth meshing with the teeth of the rotor, the teeth of the breaker plate being disposed in a curved line extending outwardly and upwardly from a point adjacent the center of the rotor to a point adjacent its periphery with the upper face of the series being concaved, together with a housing surrounding said rotor and breaker plate, and means for adjusting the spacing between the breaker plate and the rotor, said means comprising a pivotal mounting adjacent one end of the breaker plate and an adjusting screw adjacent its other end and means for driving said rotor in the direction such that the rotor teeth move toward the concaved surface of the series of teeth on the breaker plate.

2. In an ice cracking machine, in combination, a rotor comprising a flat disc rotatable on a horizontal axis, with a plurality of teeth on one surface thereof and disposed in radial lines extending outwardly from the center toward the edges of the disc, a breaker plate overlying an upper quadrant of the rotor disc and adjacent the teeth thereon, said breaker plate having a curved marginal edge lying in a plane spaced from but generally parallel with the plane of rotation of the disc and carrying a series of teeth meshing with the teeth of the rotor, the teeth of the breaker plate being disposed in a curved line

extending outwardly and upwardly from a point adjacent the center of the rotor to a point adjacent its periphery with the upper face of the series being concaved, together with a housing surrounding said rotor and breaker plate, means for adjusting the spacing between the breaker plate and the rotor and means for driving said rotor in the direction such that the rotor teeth move toward the concaved surface of the series of teeth on the breaker plate.

3. In an ice cracking machine, in combination, a rotor comprising a flat disc rotatable on a horizontal axis, with a plurality of teeth on one surface thereof and disposed in radial lines extending outwardly from the center toward the edges of the disc, a breaker plate overlying an upper quadrant of the rotor disc and adjacent the teeth thereon, said breaker plate having a curved marginal edge lying in a plane spaced from but generally parallel with the plane of rotation of the disc and carrying a series of teeth meshing with the teeth of the rotor, the teeth of the breaker plate being disposed in a curved line extending outwardly and upwardly from a point adjacent the center of the rotor to a point adjacent its periphery with the upper face of the series being concaved, together with a housing surrounding said rotor and breaker plate and means for driving said rotor in the direction such that the rotor teeth move toward the concaved surface of the series of teeth on the breaker plate.
